UNITED STATES PATENT OFFICE.

HEINRICH KOPPERS, OF ESSEN-ON-THE-RUHR, GERMANY, ASSIGNEE TO H. KOPPERS COMPANY, OF CHICAGO, ILLINOIS, A CORPORATION.

OVEN FOR GENERATING GAS AND PRODUCING COKE.

1,125,345.

Specification of Letters Patent.

Patented Jan. 19, 1915.

Application filed July 28, 1913. Serial No. 731,463.

To all whom it may concern;

Be it known that I, HEINRICH KOPPERS, a subject of the King of Prussia, and residing at Moltkestrasse 29, Essen-on-the-Ruhr, in 5 Prussia, Germany, have invented certain new and useful Improvements in and Relating to Ovens for Generating Gas and Producing Coke, of which the following is a specification.

10 The object of this invention is to provide an arrangement for efficient and easy inspected delivery of the heating gases to gas retorts and coke ovens having vertical chambers, and also to arrange the chambers as 15 near as possible to the hottest part of the ovens and to keep a clear space underneath the latter for withdrawing the coke. This object is attained according to the invention by guiding the heating gases horizontally 20 from the outlets of the regenerators to the inlets of the latter through flues surrounding the oven chambers, the regenerators extending up to the top of the oven.

According to the present invention, the 25 regenerators are preferably arranged at both sides of the oven, the heating flues forming short straight passages located intermediate the several coking chambers. The connections between the heating flues 30 and the regenerators are distributed over the entire height of the oven, thereby insuring a full utilization of the regenerators for the reason that the heating gases must pass horizontally therethrough in lieu of following a diagonal course as is the case with the ovens hitherto generally known. In order 35 to permit the formation of zones of different heat intensity at different levels, each heating flue is subdivided by horizontal partitions into a plurality of vertically aligned flues which are adapted to receive heating gases of different composition.

In the accompanying drawing: Figure 1 is a vertical section through an oven embodying my invention, and Fig. 2 a horizontal section thereof.

The oven chambers *b* arranged in pairs at the side of each other, and supported by the supports *a*, are closed at the top by covers *c* 50 and at the bottom by closures *d*; the chamber may, however, be arranged to provide for the known continuous operation. Each pair of chambers *b* is surrounded by two heating walls *e*, which are divided into separate horizontal flues *f*; the heating walls *e*

communicate by nozzle-shaped passages *g* with the regenerators *h* and *i*, which are arranged at the narrow sides of the oven chambers *b* and are distributed throughout the entire height thereof. The regenerators *h* and *i* are in all cases divided by walls *k*, which latter are connected to the heating walls disposed in front and back of the chambers *b*. Along the outer side of each of the regenerators *h* and *i*, there extends a vertical duct *v* for supplying a combustion element and discharging off gases, respectively, which duct communicates with its regenerator throughout the entire height thereof. Ducts *v* are connected by passages *m* controlled by slides *l* to the discharge flues *n*, *o*, and the pairs of regenerators are also alternately provided with air slides *p* and connections *q* to the gas conduit *r*.

In operation all the regenerators *h*, for instance, would be closed to the discharge flues *o* by the slides *l* and fed alternately in sequence of arrangement with gas from the conduit *r* and with air by opening the connections *p*. After passing through the nozzle-like passages *g* combustion of the gas and air takes place in the heating walls *e*; the gases then passing through the passages *g* into the regenerators *i*. At this side of the oven the branch connections *q* for the inlet of gas, and the slides *p* for the inlet of air are closed, while the slides *l* are open and consequently give access to the discharge flue *n*. After giving off their heat to the lattice-work filling in the regenerators *i*, the waste gases are conducted by the flue *n* to the chimney. At intervals of about every half hour the positions of the valves are reserved so that the air and gas passes in the opposite direction. Whereas the regenerators acting for the time being as accumulators of heat are traversed by a horizontal current, the uniform distribution of the gases to be heated to different heights of the regenerators may be effectively regulated by a suitable arrangement of the gas and air inlets.

I claim—

1. An oven for the generation of gas and production of coke, comprising a plurality of upright coking chambers, heating flues intermediate said chambers, regenerators communicating throughout their height with said heating flues, and vertical ducts for supplying a combustion element and

- discharging off gases, respectively, communicating with the regenerators throughout the entire height thereof.
2. An oven for the generation of gas and production of coke, comprising a plurality of upright coking chambers, heating walls intermediate said coking chambers, each of said walls being provided with a plurality of vertically alined heating flues that extend in a substantially horizontal direction, regenerators communicating throughout their height with said heating flues, and vertical ducts for supplying a combustion element and discharging off gases, respectively, communicating with the regenerators throughout the entire height thereof.
3. An oven for the generation of gas and production of coke, comprising a plurality of upright coking chambers, heating flues intermediate said chambers, two sets of regenerators located at opposite sides of the coking chambers and communicating throughout their height with said heating flues, and vertical ducts for supplying a combustion element and discharging off gases, respectively, communicating with the regenerators throughout the entire height thereof.
4. An oven for the generation of gas and production of coke, comprising a plurality of upright coking chambers, heating walls intermediate said coking chambers, each of said walls being provided with a plurality of vertically alined heating flues that extend in a substantially horizontal direction, two sets of regenerators located at opposite sides of the coking chambers and communicating throughout their height with said heating flues, and vertical ducts for supplying a combustion element and discharging off gases, respectively, communicating with the regenerators throughout the entire height thereof.
5. An oven for the generation of gas and production of coke, comprising a plurality of upright coking chambers, heating flues intermediate said chambers, regenerators communicating throughout their height with said heating flues, and vertical ducts for supplying a combustion element and discharging off gases, respectively, communicating with the regenerators throughout the entire height thereof.
6. An oven for the generation of gas and production of coke, comprising a plurality of upright coking chambers, heating flues intermediate said chambers, two sets of regenerators located at opposite sides of the coking chambers and communicating throughout their height with said heating flues, and means for admitting supply gas and air to alternate regenerators of each set, respectively.
7. An oven for the generation of gas and production of coke, comprising a plurality of upright coking chambers, heating flues intermediate said chambers two sets of regenerators located at opposite sides of the coking chambers and communicating throughout their height with said heating flues, vertical ducts for supplying a combustion element and discharging off gases, respectively, communicating with the regenerators throughout the entire height thereof, and means for admitting supply gas and air to alternate ducts of each regenerator-set.
